UNITED STATES PATENT OFFICE

94,870

DESIGN FOR A TRAY OR SIMILAR ARTICLE

Albert H. Buck, Chicago, Ill.

Application April 26, 1934, Serial No. 51,525

Term of patent 7 years

To all whom it may concern:

Be it known that I, Albert H. Buck, a citizen of the United States, residing at Chicago, in the county of Cook and State of Illinois, have invented a new, original, and ornamental Design for Trays or Similar Articles, of which the following is a specification, reference being had to the accompanying drawing, forming part thereof.

Figure 1 is a plan view of a tray or similar article showing my new design, and Figure 2 is a detail thereof in section taken on line 2—2 of Fig. 1.

I claim:

The ornamental design for a tray or similar article, as shown and described.

ALBERT H. BUCK.
